UNITED STATES PATENT OFFICE

96,266

DESIGN FOR A BOTTLE OR SIMILAR ARTICLE

James E. McLaughlin, Penn Wynne, Pa., assignor to Salem Glass Works, Salem, N. J., a corporation of New Jersey

Application April 30, 1935, Serial No. 56,627

Term of patent 14 years

To all whom it may concern:

Be it known that I, James E. McLaughlin, a citizen of the United States and residing at 224 Rockglen Road, Penn Wynne, in the county of Montgomery, State of Pennsylvania, have invented a new, original, and ornamental Design for a Bottle or Similar Article, of which the following is a specification, reference being had to the accompanying drawing, forming a part thereof.

Fig. 1 is a side elevational view of one side of a bottle showing my design;

Fig. 2 is an end elevational view of the bottle;
and

Fig. 3 is a side elevational view of the opposite side of the bottle.

I claim:

The ornamental design for a bottle or similar article, substantially as shown.

In witness whereof, I have hereunto affixed my hand and seal, this 24th day of April, 1935.

JAMES E. McLAUGHLIN.
